UNITED STATES PATENT OFFICE.

JOHN RATHGEBER AND WILLIAM J. RATHGEBER, OF NEW HAVEN, CONNECTICUT.

CURTAIN-FIXTURE.

SPECIFICATION forming part of Letters Patent No. 364,670, dated June 14, 1887.

Application filed October 16, 1886. Serial No. 216,457. (No model.)

To all whom it may concern:

Be it known that we, JOHN RATHGEBER and WILLIAM J. RATHGEBER, citizens of the United States, and residing in the town of 5 New Haven and State of Connecticut, have invented new and useful Improvements in Curtain-Fixtures, of which the following is a specification.

Our invention has for its object to provide 10 to an improved device for operating window-shades to admit light and air at the upper portions of windows; and the improvement consists in the novel construction of the parts of the shade-fixtures, as hereinafter more fully 15 described and claimed.

In the accompanying drawings, Figure 1 is 20 a front elevation of a window and shade embodying our improvements, and Fig. 2 is a side elevation of the same. Fig. 3 is a plan view 25 of a part of the shade-fixture. Fig. 4 shows the mode of securing the guide-rods and the base of the receiving-socket. Fig. 5 is a view of one of the sliding guides, and Fig. 6 shows a roll-bracket.

25 Referring to the accompanying drawings, A designates the window-shade wound upon an ordinary horizontal roll, *a'*, which is supported in the usual brackets, *b b*, of any well-known type. The brackets are supported upon guides 30 *c*, of the form shown in Fig. 5, which consist of a single piece or casting having a vertical perforation or bearing, *d*, a lateral flange, *f*, to which the bracket *b* is secured, and an arm, *g*, on the side opposite to the flange. The up- 35 per part of the arm has a horizontal socket, *i*, in which the end of a cross-bar, *k*, is driven and firmly secured, whereby the guides are joined to form a supporting hanger or fixture for the shade. The brackets are fastened to 40 the flange *f* by screws, which pass through both flanges and are secured with nuts at the back. A slot, *l*, is formed in one end of the flange *f*, for the reception of one of the bolts to provide 45 for the adjustment of shade-brackets of different sizes, and having holes at different distances apart.

Upon each side of the window-jamb *R* is arranged a straight vertical rod, *t*, with its ends received in suitable steps or sockets, *n*,

which are fastened to the jamb by screws. 50 The base of the holding-screws may, if desired, pass through horizontal slots *x* in the base of the sockets, so that the sockets may be adjusted somewhat laterally to conform to different lengths of curtain-fixtures. The guides 55 *c* are loosely fitted on the rods *t*, which are entered through the perforation *d*, and the hanger is thus adapted to slide or travel up and down along the rods.

The hanger, with its shade, is supported by a 60 cord, *s*, attached to the cross-bar *k* at its center or balancing-point. The cord passes over a pulley, *m*, which is placed vertically over the center of the cross-bar on the top or horizontal part of the jamb, and over a similar pulley, *m'*, at one end of the same horizontal part of the jamb. From this second pulley the cord hangs vertically downward along the side jamb, and is held stationary by being slipped into a suitable spring-clamp, *e*, fastened on the 70 jamb. Instead of a single cord a pair of cords may be used, one attached at each end of the cross-bar or to the guide *c*, and respectively passing over separate pulleys vertically over the points of support, and both passing over 75 the pulley *m'*, thus forming practically one cord. It is evident that instead of cords, suitable chains may be also used to suspend the fixtures.

Thus constructed and arranged, the shade 80 and hanger may be raised and lowered by the cord, and placed and held in any desired position along the window.

It is essential either that the cord should be tied to the cross-bar exactly at the balancing-point of the bar or employ two cords, as described, in order to suspend the fixture in equilibrium and prevent the guides from cramping on the rods *t*. This device allows the shade 85 to be lowered at the top to admit light or for 90 ventilating purposes, is easily operated, is not cumbersome, and is of neat and ornamental design.

We claim as new, and desire to secure by Letters Patent—

95 1. In a device for operating window-shades, the guides *c*, each provided with a vertical perforation or bearing which fits the guide-

rod, a lateral flange, *f*, having a perforation and a vertical slot, *l*, by means of which different sizes of shade-brackets may be fastened thereto, and an arm, *g*, for holding the cross-bar 5 of the sliding hanger, substantially as described.

2. In a device for operating window shades, the combination of the guide-rod *t*, the guides *c*, each fitted upon the guide-rod, and having 10 to the lateral flanges *f* and perforated arm *g*, a cross-bar, *k*, with its ends secured in the arms

g, the brackets *b*, mounted upon the guides *c*, the window-shade and its roll supported at its ends in the brackets, the pulleys *m m'*, and the operating-cord *s*, for raising and lowering 15 the fixture, all combined substantially in the manner and for the purpose described.

JOHN RATHGEBER.
WM. J. RATHGEBER.
